UNITED STATES PATENT OFFICE

161,586

COVER FOR TELEPHONES

Marie K. Laporte, Arlington County, Va.

Application August 28, 1950, Serial No. 11,971

Term of patent 14 years

(Cl. D26—14)

To all whom it may concern:

Be it known that I, Marie K. Laporte, a citizen of the United States, residing in Arlington County, Virginia, have invented a new, original, and ornamental Design for a Cover for Telephones, of which the following is a specification, reference being had to the accompanying drawing, forming a part hereof

In the drawing:

Fig. 1 is a front perspective view of a cover for telephones, showing my new design; and
Fig. 2 is a rear perspective view thereof.

I claim:

The ornamental design for a cover for telephones, as shown.

MARIE K. LAPORTE.
